DESIGN FOR A CAN OPENER

Albert M. Travis, Kansas City, Kans., assignor to
John C. Hockery, Kansas City, Mo., as trustee

Application July 12, 1946, Serial No. 131,533

Term of patent 14 years

(Cl. D22—2)

To all whom it may concern:

Be it known that I, Albert M. Travis, a citizen of the United States, residing at Kansas City, in the county of Wyandotte and State of Kansas, have invented a new, original, and ornamental Design for a Can Opener, of which the following is a specification, reference being had to the accompanying drawing, forming part thereof, in which

Fig. 1 of the drawing is a perspective view showing one side and the front of a can opener embodying my new design,

Fig. 2 of the drawing is a view showing in elevation the opposite side of the can opener shown in Fig. 1, and

Fig. 3 is a view showing in elevation the top of the same can opener.

I claim:

The ornamental design for a can opener, substantially as shown.

ALBERT M. TRAVIS.
